UNITED STATES PATENT OFFICE.

JOSEF PLEBANSKI, OF WARSAW, POLAND.

SIFTING ANTENNA.

Application filed February 2, 1924, Serial No. 690,120, and in Germany February 8, 1923.

In the telegraphy and telephony with and without wire by means of high frequency carrier current it is desired to have filters which let a predetermined range of frequency pass through without substantial attenuation but damp strongly the frequencies above and below the limits of this range of frequency.

Mutually distuned oscillatory circuits 10 have already been proposed for this object. The well known sifting chains of Campbell and Wagner are also very good means for the sifting out of predetermined frequencies. The object to be fulfilled by such chains and 15 sifting arrangements is always to produce a resonance curve which comes as close as possible to a rectangular form. It is to be mentioned that "sifting chain" and "sifting arrangement" are synonymous to the well 20 determined term "wave filter".

The present invention deals with a novel arrangement of several parallel circuits coupled together to provide a frame or open antenna and closed oscillatory circuits which 25 produce the same effects by a simpler arrangement or means than with the arrangements wherein filters and the like are at present used. The term "parallel circuits" is used in this application with the meaning 30 that all of the circuits must be simultaneously excited by the same source of electrical energy. The difference between the wave arrangement according to this invention, and the actual filters heretofore used, is 35 dependent upon the following physical phenomenon:—

If n oscillatory circuits coupled with one another in any manner are simultaneously energized by one current source with constant wave length a deformed resonance 40 curve is produced in the circuit I Fig. 1 to which for instance an amplifier or detector is connected, by the circuits 2, 3 etc., to n , if the n th circuit is varied, the circuit 1, 45 2 . . . n —1 however remaining unvaried and being tuned to the wave or slightly dis- 50 tuned, said deformed resonance curve pos- 55 ssessing, according to the designs of the circuits 1, 2 . . . n , a more or less pronounced maximum and minimum in the proximity of the resonance point.

If, however, we tune all coupled circuits for a given wave and then without changing the circuits we change the wave we can ob- 55 serve that the resonance curve will not be

the same as for one circuit only but will be a deformed one. If we choose the circuits suitably we can obtain a very great selectivity and the resonance curve can be very sharp. In this case the simultaneously excited circuits are acting as a good wave filter, if one of them is an output circuit, all waves lying in a given band of frequencies will 60 become amplified by the other coupled circuits, the waves lying outside this band will 65 be weakened by the adjacent circuits.

The connection is shown in Figs. 1 and 2 of the accompanying drawings.

Fig. 1 shows diagrammatically a preferred form of the receiving arrangement. Fig. 2 70 is a similar view showing a modified form of receiving arrangement.

Fig. 3 is a diagrammatic view showing a connection arrangement for a transmitting station.

Figs. 4 to 7 show diagrams for different 75 couplings of the circuits.

Fig. 8 illustrates diagrammatically the connection for a counter station.

Fig. 9 illustrates diagrammatically the 80 connection for precision wave meters.

Fig. 10 is a diagrammatic view showing a connection for the determination of the angle of incidence of the wave.

In Fig. 1 of the drawings a receiver arrangement is diagrammatically illustrated. The circuits 1, 2 . . . n can be coupled with one another inductively, galvanically or capacitatively, it being not necessary that the same coupling be used between the several circuits. The receiving apparatus (intensifier, detector or the like) is preferably connected with one circuit only which may be simultaneously the primary- and the end-circuit. The sifting effect and the effects which will be hereinafter described are produced merely by the vicinity of the coupled circuits, as distinguished from the so-called differential connections, in which the difference- or sum-current is utilized by several 85 parallel circuits. 90

The effect of the coupling arrangement according to the invention is based on the fact that when a circuit, with which the receiving apparatus is connected, is influenced by adjacent circuits, with which it is coupled in any manner, the first circuit receives, at a predetermined dimension of the adjacent circuit, for a predetermined wave range more of the energy from the source 100 105 110

of current than if it were alone. For the wave trains, which lay outside this range, the relative resistance of this circuit becomes greater in proportion to the resistance which it would have if it were alone. It is however necessary, as already mentioned, that the adjacent circuits are also excited from the sources of current and that all the circuits react only insignificantly upon the source of current.

The connection arrangement possesses, besides its simplicity, the advantage that it is well adapted to serve as wave filter for wireless telegraphy and telephony and effects further a good interference elimination as it damps all waves (for instance disturbing waves, atmospheric waves and the like) much more strongly than a single circuit, for instance an antenna circuit could do this.

The circuits may be constructed as frame coil circuits or as antenna circuits (Fig. 2).

For a transmitting station the connection arrangement according to the invention is preferably constructed as shown in Fig. 3. To the circuits 1, 2 and 3, which is shown as an open antenna circuit, energy is impressed from a high frequency source S in parallel, the coupling relations between the circuits being indicated by arrows. It is to be seen that the circuit 1 is simultaneously the output circuit having the aerial and the earth terminals. In order to avoid reaction upon the high frequency current source S due to the parallel circuits especially when closely coupled, either a high frequency machine or separately controlled thermionic valve transmitters are used in this case, i. e. current supplying sources which by the tuning of the parallel circuits are not affected. Either several dummy antennæ and one radiating antenna or several radiating antennæ and several dummy antennæ or only several parallel radiating antennæ may be used. However, the radiation of the wave spectrum can take place only from one of the antennæ circuits connected in parallel.

The phenomena which occur in such a connection arrangement are illustrated in the diagrams shown on the drawings:

Fig. 4 shows for instance the course of the energy reception or of the energy consumption of the circuit 1 ($J_1^2 R_1$), tuned to the waves and coupled with the receiver, and of the circuit 2 ($J_2^2 R_2$), it being assumed that the circuit 1 is tuned to the waves (or slightly distuned), circuit 2 being altered. The current in the circuit 1 drops at first to a determined minimum whereupon it increases rapidly to a maximum. It drops again hereafter. Whether at first the minimum and later on the maximum of the current comes into existence depends on the phase-displacement between the electromotive forces which are excited in the corresponding circuits.

If in the arrangement shown in Fig. 8 in the receiver 1 a minimum of current occurs at first and then a maximum, the inverse will take place in the receiver 2 as the phase-displacement in the receiver 2 amounts to 180° or as at the same phase of the E. M. F. the inverse coupling is produced. The resonance curve indicated in dotted lines in Fig. 4 shows the curve of the current or the energy consumption of the second current if it were alone. If it is coupled with the circuit 1 its resonance curve is much flatter, the proportion of the energy consumption in circuit 1 (useful circuit) to the energy consumption in circuit 2 in the maximum range is therefore very great and consequently also the efficiency of the whole arrangement is very favorable in comparison with the commonly used chain connections which consume very much energy and in which so high degrees of efficiency as in the connection according to the invention can never be obtained. It is evident that the parallel circuits must be of convenient dimensions, so that the coupling between the circuits is in a certain proportion to the damping and the other values.

Fig. 5 shows a group of curves for different couplings of the two circuits with the same damping.

Fig. 6 illustrates the sifting effect.

Three circuits are supposed to be excited under the above mentioned conditions. All curves relate only to the first circuit which is connected with the receiving apparatus. The circuits 2 and 3 are coupled and of corresponding dimensions and they take up energy from space simultaneously with the first circuit. If the exciter wave is altered and if the resonance wave for the first circuit is traced when the other two circuits are removed, the curve I is obtained. If the three circuits are coupled with one another and if the resonance curve for the circuit 1 is traced again, the curve II is obtained from which the reduction of the resistance and the equally strong receiving for a determined wave range can be seen as well as the intensified damping of the frequencies outside this range.

The curve III shown in dash and dot lines illustrates the same curve as curve I but with the difference that the maximum value of the same has been supposed as equal to that of the curve II.

The connection arrangement of oscillation circuits according to the invention may be used also for other purposes. If for instance a receiving antenna is built in such a manner that it consists of two frame antennæ, of which the first one possesses a greater resistance than the second one, and if the receiving apparatus is connected with the first antenna a curve of energy consumption is obtained in dependency of the wave

length as illustrated in Fig. 7. If the several values are selected accordingly the difference between maximum and minimum can be very great (for instance amount to a 5 million times and more). A receiving apparatus of this type can therefore be put up at short distance from the transmitter without being disturbed from the same if the transmitter works with a wave which corresponds 10 to the minimum of the system; the receiver can well receive the wave of the counter station which corresponds to its maximum. The two frame antennæ on the counter station must however be coupled inversely in 15 order that the two stations can work together. This connection is diagrammatically illustrated in Fig. 8.

The arrangement described can be carried out also with several parallel circuits. If 20 the receiving apparatus works with return coupling reception the return coupling coil may be re-coupled with one or several of the circuits working in parallel.

Such circuits may be used also for the 25 building of precision wave meters (Fig. 9). If for instance two such circuits are excited from one source of current to be measured, oscillations are produced in both circuits according to the above indicated curves. If 30 the first circuit is tuned to the wave and if the second circuit is made to act, this circuit being repeatedly closed and opened in one second by means of a suitable ticker, the 35 interruptions are strongly heard at the moments of the minimum and maximum but weakly only at all other points, if however, the tuning of the second circuit is situated exactly at the point where the curve intersects the line $M-o$, the interruption is not 40 heard.

When the single values are correctly determined the error of the measuring of the second circuit can amount only to several percent of the curve of measuring of the first 45 circuit. If at the measuring of the circuit I an error of 3% has occurred the error at the re-measuring with the circuit II is for instance only 0.03%. This method is well

adapted to be used for undamped oscillations.

The maximum and minimum as well as the zero point (point of intersection with line $M-o$) of the curve depends on the amplitude of the E. M. forces, that is on E_1 and K_2 . If two controlling antennæ (frame 55 antennæ and the like) standing at a predetermined angle to one another the angle of incidence of the wave can be found by the connection shown in Fig. 10.

At a predetermined selection of the individual values L , C , E phase displaced currents of such a kind can be produced in the circuits that a rotating field can be produced with the aid of specially located coils this being applied for energy transmission, for 60 measuring purposes or the like.

I claim:—

1. An aerial arrangement consisting of a plurality of tunable circuits coupled with one another, one of said circuits being an 70 output circuit, the totality of said circuits being designed to be energized from the same source of high frequency currents, means for coupling said circuits and determining their values in such a manner that 75 the aforesaid output circuit will receive, amplify and transmit without substantial attenuation a given range of frequencies and will damp all frequencies lying beyond the limits of said band.

2. In a two-way signalling system for 80 radio-communication in opposite directions, according to claim 1, means for tuning the transmitting stations to the waves corresponding respectively to the maximum of 85 the resonance characteristic curve determined by a wave filter apparatus, and means in the respective receiving stations for reversing the maximum and minimum relation of said curve in view of the maximum and 90 minimum relation of the other receiving station.

Signed at Warsaw, this 11th day of January, 1924.

JOSEF PLEBANSKI.
